UNIT TRANSMITTER PRINTING AND
SIGNALING SYSTEM

Manfred W. Muehler, Nutley, N. J., assignor to
American District Telegraph Company, Inc.,
Jersey City, N. J., a corporation of New Jersey

Application January 12, 1938, Serial No. 184,595

43 Claims. (Cl. 234—27.5)

This invention relates to systems for operating printing recorders and more particularly to an improved signaling and recording system of the unit transmitter type based on the system disclosed in applicant's prior Patent No. 2,109,273, granted February 22, 1938.

An object of the invention is to provide a printing-type recorder which prints a record showing the class or type of the supervisory or alarm transmitter, its condition whether normal or abnormal, its number, and the date and time of its operation in plain language and in Arabic numerals instead of a code as obtained with a pen or punch register.

Other objects are to provide separate alarm and supervisory circuits, both working in conjunction with the same printer and providing for preferential operation of alarm signal transmitters. This increases the reliability of the more important alarm service, as all alarm transmitters are concentrated on their own circuit which will, therefore, be shorter and less exposed to troubles. The preferential feature insures, that alarm signals will under all normal or trouble conditions be given first consideration in recording, thereby eliminating possible delay in reception.

Automatic trouble adjusting means are provided which, in the case of a break of one or all of the three circuit wires, adjust the system for operation under that condition. Independent means are provided for the alarm and the supervisory circuit and the system is capable of maintaining operation of all transmitters even with breaks in all of the three wires of both circuits at the same time. Automatic restoration is effected as soon as the particular circuit is repaired.

Further novelty resides in the fact that the impulse means which provides the operating impulses is a double speed device with provision for automatic speed change from high to low speed. Normally the operation of the system will be at the higher speed of 5 impulses per second, for instance; however, in case of signals, for instance fire alarm signals, that sound the code on gongs the speed is automatically reduced to a speed at which the strokes of the gong can be distinguished and counted. This has the advantage of being able to retain the higher speed of operation except for signals where gong operation is involved. As at the end of each audibly coded signal the higher speed is automatically resumed, this feature also serves to appreciably reduce the time interval between successive rounds of the audibly coded alarms, resulting in substantially

uniformly spaced audible coded alarm signals and speeding up the transmission rounds of audibly coded alarms.

Another improvement relates to the mode of operation of certain types of transmitters arranged for transmission of repeated alarm signals, as in the case of waterflow transmitters. These transmitters are arranged with a code wheel having an "alarm" code on one side of the wheel and a "restoration" code on the other half as in the case of supervisory transmitters. If the transmitter is also arranged for three round alarm signal operation, for instance, the first round will come in as an alarm signal, the second as a restoration signal and the third again as an alarm signal, each signal being transmitted by one half of the wheel. An object of the present invention is to provide, at the receiving station, converting means for converting this "restoration" signal into an alarm signal and recording it as such, and perform same as an alarm signal, viz., tap out the code on the gongs. In case of a genuine restoration signal, only the one restoration signal is transmitted, and the converting means do not become effective. Thus the signal performs as required for a restoration signal and fails to tap out its code on the gongs, in which case the complete restoration signal will be transmitted at the higher speed. This arrangement considerably simplifies the design of those transmitters which would otherwise require a double set of code wheels and coding contacts and an additional geared controlling cam.

Various selective and other novel features will be apparent from the following representative description.

This system is called a unit transmitter system because it makes use of an individual transmitter for each alarm or supervisory device from which indications are required. Each transmitter is directly attached to the particular device which operates it. The various transmitters of a system are interconnected by means of one or more three-wire loop circuits which originate at and return to the control center.

The transmitters operate in conjunction with control equipment located at the control center in a non-interfering and successive manner to record a signal on a printer recorder at the control center and to perform other functions.

The transmitters are driven by current impulses from the control station. The basic type of transmitter is the supervisory type. It has two codes arranged on the circumference of its code wheel. One code is transmitted when the associated de-

vice is operated to its alarm condition and the other when it is restored to its normal position. The difference of the two codes consists in 4 additional teeth in the second digit for the restoration signal. The impulses transmitted are strong and weak, weak impulses representing spaces. The starting of the transmitter is controlled through a transfer cam switch, the position of which is reversed during the transmission of a signal, in conjunction with the transfer switch operated by the supervised device. Other transmitters will be referred to hereinafter. Code impulses from the transmitters control the impulse operated type carriers at the control station.

A delinquency indicator is provided consisting of a stepping mechanism which is advanced one step every minute and restored automatically when a night watch signal comes in. If the night watch signal fails to come in within the proper time interval, an associated transmitter may be operated to record a delinquency signal on the tape. Operation of a night watch box will then reset the delinquency indicator and record a restoration signal.

All supervisory signals, that is, signals from sprinkler supervisory devices and delinquency signals, are arranged to register on a totalizer which is advanced one step when one of the above-mentioned devices runs in an alarm signal and is moved back one step when one of the devices is restored to normal. It thus indicates at all times the number of abnormal supervisory devices.

A ground detector relay is connected to the center of the ungrounded battery. The other terminal of the relay coil is connected to ground. A ground on any external circuit will operate this detector relay and give a lamp and buzzer signal. The buzzer can be silenced by turning the associated lamp switch. When the ground is removed from the system, the light goes out and the buzzer rings again until silenced by turning the switch back to normal.

Since no other ground exists on the system except through the high resistance coil of the ground detector relay, a single ground will not interfere with the operation of the system especially as the ground connection is removed from the detector relay while a signal is being transmitted.

In the drawings, the figures show diagrams of the system, transmitters and signals.

Figs. 1 to 5 together show the control station, printing recorder and two types of transmitters.

Fig. 1 shows the supervisory circuit and transmitters;

Fig. 2 shows the alarm circuit and transmitters;

Fig. 3 shows principally the control station means for supplying the impulses to the transmitter circuit and the type carrier setting means;

Fig. 4 shows principally the routing relays for supplying the impulses to the respective type-carrier setting means;

Fig. 5 shows the printer and totalizer;

Fig. 5a shows the detailed construction of the printer of Fig. 5;

Figs. 6 and 7 respectively show the night-watch and fire-alarm transmitters;

Figs. 8 to 13 are diagrams representing strong and weak impulses of types of signals as titled, the upper solid line portions representing strong impulses, the dotted lines representing weak im-

pulses, the number stated being the transmitter number.

The transmitters and their operation are similar to those disclosed in the above mentioned application.

The mechanical elements of the printer are similar to well known types of printing recorders and to those shown in my prior Patent No. 2,126,025, dated August 9, 1938, and the application of Johnson et al., Serial No. 507,898, patented September 12, 1939, No. 2,172,511.

Supervision

The supervisory circuit for the common and starting lines of the supervisory circuit can be traced as follows: from plus battery through contact 301 (upper left of Fig. 3) over wire 138, (lower left of Fig. 1) out over the ST loop and back to the control center, through make contact 101, through the coil of relay 102 over the C line and back to the control center to minus battery (Fig. 1). Relay 102 is normally held energized through this circuit supervising the ST and C lines.

The supervisory circuit for the R line can be traced from plus through the right-hand winding of main starting relay 103, (upper right of Fig. 1) back contact 104, left-hand winding of relay 103, through the R line, and corresponding contacts 105 (Fig. 1) of the line transmitters, back to the control center through make contact 106, through the middle winding of relay 103, through the coil of relay 107, (lower right of Fig. 1) over wire 108, through contact 302 (upper part of Fig. 4) to minus battery. Relay 107 (Fig. 1) is normally held energized in this circuit supervising the "R" line. Although current is flowing through all three windings of relay 103, it is to be noted that the middle winding has a number of turns equivalent in effect to the sum of the other two windings of relay 103 and is connected opposingly so that the effect on relay 103 is neutralized.

Similar supervisory circuits can be traced for the alarm circuit involving supervisory relays 202 and 207 at the lower right of Fig. 2, as will be evident from the above.

Transmitter start

The transmitter of Fig. 1 is similar to that of applicant's Patent No. 2,109,273, issued February 22, 1938, and comprises a pair of stepping motor magnets 10, 11 adapted to oscillate the armature 12 and by means of a pawl and ratchet, is adapted to rotate step-by-step a shaft carrying a master cam 14, a transfer cam 15 and a code wheel 16 which may be toothed on the alarm side as shown in Fig. 8, and on the restoration side as shown in Fig. 9.

Assuming that the operation of a transmitter is initiated, say for instance, the supervisory transmitter of Fig. 1 shown connected to the supervisory line at the upper left-hand side of Fig. 1, by a change to the right of the transfer element of the device switch 109 of the associated device to be supervised, the following circuit will be closed from the ST line, where plus polarity of the battery is available at contact 301 (Fig. 3), as has been explained, through the device switch 109, the normally closed contact 110 of the transfer cam contact, through the normally closed master cam contact 111, and the right-hand magnet coil of the transmitter to the C line where minus polarity is available as shown. The transmitter magnet is energized and attracts its

armature closing its contact 112 and engaging the next tooth of the ratchet wheel preparatory to advancing it one step when subsequently de-energized. By closing contact 112, the R line is connected through contacts 105, 105', 112 and the armature 12 to the tap of the right-hand transmitter coil and the current flow in the "out" side of the R line is considerably increased. This has the effect of increasing the current through the two outer windings of relay 103 to such a degree that relay 103 will pick up.

Relay 103 locks from plus in through its right-hand winding, contact 113, resistor 114, over holding conductor 115 and through contact 303 of relay 315 to minus. It also energizes relay 116 from minus through contact 117 and its middle winding. This relay 116 opens the running line at contact 104 and also locks in from plus through its left-hand winding, make contact 118, resistor 119, to holding conductor 115. The break in the R line causes relay 107 to drop out and light a lamp 107I through an obvious circuit.

Start of pulsing relays

The main pulsing relay is 304 which operates in conjunction with relay 305. These relays start their operation as soon as contact 120 of relay 116 closes a circuit from plus over wire 121, through contact 306' of relay 315', over conductor 307, through contact 401 of relay 432, over conductor 402, through resistor 308 and the left-hand winding of relay 304 to minus. Relay 304 operates and by opening its back contact 309 removes the shunt from the left-hand winding of relay 305 permitting it to operate from minus through resistor 310, left-hand winding of 305 to plus obtained from conductor 402 as traced above. When contact 311 closes, the winding of relay 304 is shunted out and relay 304 deenergizes with a slight delay. At this time, a circuit is closed from plus through contact 312 of relay 305, contact 313, conductor 314', back contact 322, conductor 314, contact 123, over conductor 124 and through the coil of the supervisory master relay 315 and contact 316' to minus. Relay 315 operates. This relay closes a locking circuit for itself through contact 317 to plus over conductor 402 to keep itself energized when contact 312 or 313 opens. By opening its contact 301, relay 315 removes plus battery from the starting line causing the transmitter previously operated to release its armature and advance its ratchet wheel one step. It will be noticed that this happens after a time delay following the operation of relays 103 and 116, giving sufficient time to the transmitter magnet to operate properly and for other functions which will be subsequently explained. The opening of the starting line causes the release of relay 102.

The first step of the transmitter changes the position of the master cam contacts to the operated position. The right-hand magnet coil of the transmitter is now connected to the "out" side of the running line through contact 125 while the left-hand magnet coil is connected to the "in" side of the running line through contact 126. The running line being open on the "out" side at contact 104 of relay 116, and on the "in" side at contact 302 of relay 115 which has been opened, no current is supplied to either of the coils of the transmitter at this time.

Impulses transmitted through the R line

Following the release of main impulse relay 304 which energized relay 315, the coil of relay

305 is shunted by back contact 309 causing relay 305 to release with a slight delay. With contact 311 of relay 305 opening, the shunt is removed from relay 304 permitting it to energize again. 5 At this time an impulse is transmitted to the transmitter, the circuit of which can be traced as follows: from plus through make contact 318, the coil of marginal operating relay 319, conductor 319', contact 320, over conductor 321, make contact 121 of relay 103, left-hand winding of relay 103, the R line, in series with the master cam contacts similar to 105 of intermediate transmitters, if there are any, through contact 125 of the operated transmitter and its right-hand magnet coil to the C line and minus. The transmitter magnet is thereby energized. As at this time the code wheel contacts of the transmitter are not yet closed, this impulse will be of low intensity, not capable of operating the marginal relay 319. However, enough current flows through the left-hand winding of relay 103 to keep it energized. It will now be shown that at this time relay 103 has to depend on this left-hand winding for its energization. At the time 15 relay 315 is energized, the locking circuit for the right-hand winding of relay 103 is transferred from minus battery through contact 303 to minus battery through contacts 322 and 324, contact 323 in multiple with 324 being open at that time. 20 It may be noted that contacts 303, 322 are of the make before break type thus preventing momentary interruption of the holding circuit of relay 103 when relay 315 picks up. A short time after relay 304 is reenergized, at the time of the transmission of an impulse over the R line, relay 305 is also reenergized as relay 304 again removes the shunt from the winding of relay 305. Both contacts 323 and 324 are thus opened depriving the right-hand winding of relay 103 of current. 25 However, as indicated above, relay 103 stays energized because of the current flowing through its left-hand winding.

Relay 305 energizing again shunts the coil of main impulse relay 304 which drops out with a slight delay. This successive operation of relays 304 and 305 now continues for the full time of the signal transmission. Every time 304 releases, the line impulse is interrupted by the opening of contact 318, and the transmitter releases advancing its ratchet wheel one step. Since back contact 324 of impulse relay 304 is arranged to close prior to the opening of front contact 318, the locking circuit for relay 103 is not even momentarily interrupted.

55

First coding impulse

In this way the transmitter will be operated step by step until the first tooth of the first digit of the code wheel closes its contacts shunting the upper portions of the transmitter magnet coils. The next impulse will, therefore, be of considerably greater intensity and will be a signal impulse sufficient to operate the marginal relay 319. By closing its make contact 325, relay 319 energizes the coding relay 403 from minus over conductor 326, through its two windings in series and to plus at conductor 307. Relay 403 locks in from minus through its contact 404 and its left-hand winding to plus over conductor 307, which is now connected to plus as above explained. Fig. 8 shows an example of a supervisory alarm signal.

70

First impulse to printer

When impulse relay 304 subsequently releases, 75 the first stepping magnet of the printer PS1 of

the first digit type carrier receives an impulse from plus through back contact 327, over conductor 328, contact 405 of relay 403, back contact 406 of the first shifting relay 432 (bottom of Fig. 4), conductor 407 and the coil of the first stepping magnet PS1 to minus. The latter advances its ratchet wheel one step and brings the stepping wheel retaining pawls into operative position to prevent retrograde movement and also closes latch contact L which stays closed until the printer has been reset to normal.

Second coding impulse from supervisory transmitter

When impulse relay 304 is energized for the next line impulse, a circuit is also closed from plus through make contact 329 of relay 304, over wire 330, break contact 408, break contact 409, right-hand winding of the routing relay 410, over conductor 411 and latch contact L to minus. Relay 410 is thus energized. As relay 319 is again energized, due to the fact that all supervisory transmitters have a number of consecutive teeth in the first digit, a circuit is closed from plus through contact 307 of relay 315 over conductor 369, contacts 411', 412, 413, 414 of energized relay 410, conductor 415, contact 331 of relay 319, conductor 332, contact 416 and the left-hand winding of the first converting relay 417 to minus. Relay 417 is thus operated and locks in from minus through its contact 418 and right-hand winding to plus over conductor 369.

When relay 304 subsequently releases, a circuit is closed from plus through contact 333, over conductor 334, contact 419 of relay 410, the left-hand winding of relay 410, over conductor 420 and through contact 335 of relay 315 to minus, holding relay 410 energized. It is to be noted that contacts 329, 333 of relay 304 are of the make-before-break type so that the circuit for the left-hand winding of relay 410 will be closed before that of the other one is opened. Another circuit is closed at this time from plus at conductor 334 through contact 421 of relay 432, contact 422 of relay 410 and through the right-hand winding of relay 423 to minus at conductor 420 and contact 335 of relay 315, thus operating relay 423.

At the same time another impulse is transmitted to the first stepping magnet PS1, of the printer over the previously traced circuit through back contact 327 of relay 304.

The third and following code impulses of first digit

When the next impulse is transmitted to the line circuit back contact 333 of relay 304 is opened deenergizing the left-hand winding of relay 410, and relay 410 is caused to release since the previously traced operating circuit through make contact 329 of relay 304 and back contact 408 of the third shifting relay 423 for the right-hand winding of relay 410 is no more closed. However, relay 423 remains energized from plus at conductor 330, through contact 424 and the left-hand winding of relay 423 to minus at conductor 411. When relay 304 releases again, another impulse is transmitted to the first stepping magnet of the printer. The former operating circuit of relay 423 is now open at contact 422 of now deenergized relay 410, but another circuit is closed instead through contacts 445 of relay 410 and 446 of relay 423 to plus at conductor 334. The following impulses of the first digit will have no other effect except operating the transmitter

5 and the first stepping magnet of the printer for additional steps. Relay 423 will remain energized through its right-hand winding during the time the relay 304 is deenergized and through its left-hand winding during the time relay 304 is energized.

First shifting space

When the space following the first digit group of teeth is brought into position opposite the coding wheel contacts, these will remain open and the subsequent line impulse will be of low intensity, as indicated at the sixth impulse of Fig. 8. This low intensity impulse is not capable of operating marginal relay 319 and the low intensity impulses correspond to the absences of impulses in most other systems, and are herein referred to as spaces as contrasted with the stronger signal impulses. Both windings of coding relay 403 will now be connected in multiple as follows: the right-hand end of the winding is connected over conductor 326 through contacts 335, 336 to plus at conductor 402, the left-hand end being connected to plus at conductor 307, while the common in the middle is connected to minus through contact 404. The flux set up by the two equal windings will be of opposing direction neutralizing one another and causing relay 403 to release.

When relay 304 subsequently releases, a circuit 30 is closed from plus through contact 333 over conductor 334, through contacts 425, 426, 427, 428, resistor 429 and through the right-hand winding of the second shifting relay 430 to minus, operating relay 430. No impulse is transmitted 35 to the printer at this time as contact 405 of relay 403 is open.

Second digit

The next impulse transmitted over the line 40 will again be of a greater intensity as the first tooth of the second digit operates the code contacts to the closed position. Relays 319 and 403 are operated as before. The above traced circuit of relay 430 is interrupted at this time but another circuit is closed for its other winding from plus at conductor 330 through make contact 431, the left-hand winding of relay 430 to minus at conductor 411, maintaining relay 430 in an energized position. At the same time, a circuit is closed for relay 432 from plus at contact 431 through the left-hand winding of relay 432 over conductor 433, through contact 337 of relay 315 over conductor 411 and through latch contact L in the printer to minus, operating relay 432. This relay locks in from plus through its other winding and contact 434 to conductor 411 and contact L. Contact 401 opens but multiple contact 435 being closed, the circuit for the pulsing relays and relay 315 remains closed.

When relay 304 subsequently releases, an impulse is transmitted to the second stepping magnet PS2 of the printer from plus through contact 327 over conductor 328, through contacts 405, 436, 437, 438, over conductor 439 and through the coil of the second stepping magnet PS2 to minus. Relay 430 is maintained energized through its right-hand winding but now from plus at conductor 334 through contacts 440, 441, 442.

70 Subsequent code impulses will operate the transmitter and second stepping magnet of the printer for additional steps but no change in the routing relays 410, 423, 430, 432 will occur until the space following the second code digit causes the next shift impulse, relays 403, 423,

430, 432 remaining energized in the meantime.

Third digit

Relay 403 is deenergized when the low current impulse following the second code digit is transmitted over the line. When relay 304 releases following it, relay 430 is deenergized as the circuit of its right-hand winding is opened due to the opening of contact 440.

When the next impulse is transmitted to the line circuit, the first tooth of the third digit closes the code wheel springs of the transmitter again, causing relays 318 and 403 to operate. At the same time the relay 410 is reenergized from plus at conductor 330 through contacts 443, 444 and the right-hand winding of relay 410 to plus at conductor 411.

When relay 304 subsequently releases, relay 410 remains energized through its left-hand winding and contact 419 as before. At the same time, relay 423 is deenergized since the circuit for its right-hand winding is open at contacts 445 as well as 421. Contact 435 is opened; this, however, has no effect since it is in multiple with 447 which is now closed, maintaining the operating circuit of the pulsing relays and relay 315 closed. Furthermore, an impulse is transmitted to the third stepping magnet PS3 of the printer which can be traced from plus through contact 321, over conductor 328, through contacts 405, 436, 448, over conductor 449, and the coil of the third magnet PS3 to minus. The following code impulses of the third digit will operate this stepping magnet and the transmitter for additional steps while the routing relays maintain their position with 410 and 432 energized.

Fourth digit

Following the third digit, a space is encountered by the code springs of the transmitter code wheel causing a low current impulse on the line, not capable of operating relay 319. Relay 403 releases. When relay 304 subsequently deenergizes, relay 430 is energized again from plus at conductor 334 through contact 425, 448, 442, resistor 429 and right-hand winding of relay 430 to minus.

When the next impulse is transmitted over the line, the first tooth of the fourth digit will cause operation of relays 319 and 403. At the same time relay 410 is deenergized as the circuit for its right-hand winding is open at back contact 443. Relay 430, however, remains energized through make contact 431 as earlier described.

Contact 447 is now open but shunted by 449 maintaining the circuit for the pulsing relays and relay 315 closed.

When relay 304 subsequently releases, an impulse is transmitted to the fourth stepping magnet PS4 of the printer from plus through back contact 321 over conductor 328 through contacts 405, 436, 437, 450, conductor 451 and the coil of the fourth stepping magnet PS4 to minus. The following impulses of the fourth digit advance this magnet and the transmitter a corresponding number of steps.

Printing and clearing operations

When a low current impulse is transmitted over the line due to the space following the last tooth of the fourth digit of the code wheel, relay 319 again fails to operate causing the release of relay 403. Contact 449 of relay 403 now opens but this has no immediate effect as it is shunted by contact 338 of relay 304. However, when the

relay 304 subsequently releases, this shunt is removed. With the subsequent release of relay 305 an alternative path from plus through contact 312 and 338 (of relay 315) for the pulsing relays and relay 315 is opened at contact 312 causing the pulsing relays to cease operating and relay 315 to release. Contact 367 of relay 315 opens and removes plus from the holding conductor 369 of relay 417, but plus is still being supplied by contact 452 of relay 430 which is still energized from plus at conductor 334 through contacts 453 of relay 423, 441 of relay 430, 442 of relay 430, resistor 429 and the right-hand winding of relay 430 to minus. At the instant relay 305 releases, a circuit is closed from plus through contact 338, conductor 334, contacts 425, 426, 454, over conductor 455, through contact 340, over conductor 341, through contact 456, over conductor 457, through the printer cut-out contact PC and the printer magnet PR to minus. The printer magnet is energized causing the signal already set up on the four type wheels of the printer to be printed on the tape.

The totalizer

At this time it may be explained that the second type wheel of the printer operates a cam 500' with contacts 501 and 502. For the chosen designations of the printer wheels the cam 501' is so arranged that normally, and if magnet PS2 is operated for 1, 2, 3 or 4 steps, contact 501 is closed and 502 is open and if operated for more than 4 steps, contact 502 is closed and 501 is open. Assuming that magnet PS2 was operated 3 times (corresponding to an alarm signal with "3" as the first numeral of the device number) the following circuit can be traced at the time the imprint magnet is operated: from conductor 341 to which plus polarity was traced above, through contact 458 over conductor 459, through contact 501 and the adding magnet 510 of a so-called totalizer over conductor 505, through contact 463, conductor 464 and contact 342' to minus, operating it. The totalizer is a step-by-step device operating a common indicator shaft in either direction, depending on whether actuated by one or the other of its magnets. It is used to indicate the total number of supervisory devices in an abnormal condition at any given time. The second type wheel prints simple numbers in its first printing positions and duplicates these numbers with the indication "Rest." meaning restored at the other positions. Therefore when the same transmitter which sent the signal of Fig. 8 sends a restoration signal (Fig. 9), the second digit would have 7 impulses. The second type wheel would then bring "Rest. 3" into printing position. The subtracting magnet of the totalizer would then be energized instead of the adding magnet, setting the indicator back one step.

A multiple circuit may also be traced from plus at conductor 459 through conductor 459' the resetting magnet 465 of the night watch delinquency indicator, which will be mentioned again later, over conductor 466 and through the lower winding of special attention relay 343 to minus. Magnet 465 does not operate in this circuit because of the high resistance of the winding of relay 343, but this relay does, locking in from plus through its upper winding, contact 344 and contact 345 to minus. Through obvious circuits relay 343 operates a light 348' and a buzzer 348 by closing contacts 346 and 347.

This relay will stay energized and maintain its

visual and audible signal until the attendant operates a key switch operating a transmitter which may be similar to that of Fig. 6 and which records an acknowledgment signal on the tape. Contact 345 is opened by hand or may be opened by this transmitter momentarily by means of a cam 345' (Fig. 6) on the transmitter shaft which operates near the end of the transmitter cycle, causing relay 343 to release. This switch and cam would not be present on the night watch transmitter mentioned hereinafter.

When the imprint magnet operates, it closes contact 503 and supplies minus polarity over conductor 504 to the left end of the right-hand winding of relay 430 causing a shunt across this winding and making it release with a slight delay. Contacts 456 and 458 open and deenergize the imprint and totalizer magnets, and the armature of the imprint magnet releases and operates means which move the paper tape forward one step.

Contact 452 opening removes plus from locking conductor 330 of relay 417, causing it to release.

A circuit is now closed from plus at conductor 341 through contacts 460, 461, conductor 462, coil RL of the release magnet in the printer, through contact 506 to minus, operating the release magnet. This magnet releases and restores the printer type wheels to normal and opens latch contact L. The latter causes relay 432 to deenergize by opening the circuit of its right hand-winding.

When contact 401 of relay 432 closes the circuit of the pulsing relays, these will start their operation with the energization of relay 304. It will be noted that the operation of the pulsing relays has been stopped until the completion of the printing and clearing operations of the recorder. This feature makes these operations reliable and independent of the speed and impulse duration of the pulser and in conjunction with the printer cut-out contact PC, which is arranged to open automatically when the printer head is lifted, for changing paper for instance, prevents further signals from coming in without the possibility of mutilation of line impulses, which could occur, were the cut-out switch put directly into the pulsing circuit. When relay 304 operates for the first time after restoration of the printer, no impulse is transmitted to the line as contact 320 of relay 315 is open. However, the starting relay 103 has been maintained energized as its locking circuit through its right-hand winding, contact 113, resistor 114 and conductor 115, has been transferred by contact 303 of relay 315 directly to minus. Subsequently, relay 305 is energized and 304 deenergized again. At this time the original operating circuit for relay 315 is closed from plus through contacts 312 of relay 305, 313 of relay 304, conductor 314', contact 222, conductor 314, contact 123 of relay 116, conductor 124, coil of relay 315 and back contact 316' to minus, unless a signal is waiting to be recorded on the alarm circuit, in which case contact 222 is opened and 223 closed, as will be explained with more detail later in connection with the preferential arrangement for alarm signals. Assuming that this is not the case, relay 315 is energized and again locks in through contact 317 to plus again available over conductor 402. Impulses are again transmitted through contact 127 to the "R" line circuit as contact 320 of relay 115 is now closed. Except in cases where there is only one space between the last tooth of the fourth digit of the transmitter code wheel and its following home

position, the transmitter is at this time still in the running condition, i. e., with the master cam contacts in the operated position. The transmitter will again be operated by the line impulses which, however, will all be of low intensity since no more teeth are provided on the code wheel. Eventually the transmitter reaches its home position where the master cam 14 and its contacts are restored to the position as shown on the drawings and the R line circuit will be open except in a case where another transmitter is already connected to the R line waiting to transmit its signal, as will be explained later. The transmitter just operated is now again in its home position except that its transfer cam in the meantime has operated the transfer cam contact to the other side to be ready for a new start when the device switch is thrown back. In transmitting its signal, the transmitter code wheel has completed approximately one half revolution.

These above mentioned resetting impulses have no effect on the control center relays and printer. When the transmitter has disconnected itself from the running line and providing no other transmitter is already waiting on the R line to send its signal, the impulse circuit will be open when the next line impulse is transmitted. Relay 103 will release as its left-hand winding will carry no current, the right-hand winding likewise being deenergized since it in the meantime has been switched by contacts 303, 322 of relay 315 from minus to minus through the contacts 323 and 324, of relays 305 and 304, by the reenergization of relay 315, and as both these contacts are then open. The circuit of the middle winding of relay 103 is also open, as contact 302 of relay 315 is open. Relay 103 deenergizes and causes relay 116 to release by opening contact 117 and breaking the circuit of the center winding of 116. The common circuit of the pulsing relays and relay 315 is at this time maintained energized from plus through contacts 312 of relay 305 and 339 of relay 315 in series but is opened at the time relay 305 releases the next time. When this happens, relay 315 restores to its normal deenergized position. The line circuit is now normal again and relays 102 and 107 pick up.

All relays are now in their normal position except relay 343 (right of Fig. 3); as explained above, it is deenergized by the operation of the acknowledgment transmitter.

The system is now ready for a new operation. If, for example, the device switch of the above-mentioned supervisory transmitter of Fig. 1 is thrown back to the position shown, a new starting circuit is closed through the other side of the transfer cam contact starting a new cycle in the manner described above. The only difference will be that a different code is transmitted, the restoration code having four more impulses in the second digit, as shown by Fig. 9, thus in Fig. 9, bringing the designation "Rest" in position to be printed.

Night watch transmitter

The operation of night watch transmitters (Fig. 6) which are also connected to the supervisory circuit, is the same as that of the supervisory transmitter as explained above except for the following points:

As shown by Fig. 6, the starting circuit is closed by a latch contact 71. This contact is closed when the associated latch 72 is tripped as the watchman operates the box with his key 73. The latch contact is restored to its normally open

position by a restoring cam 74 near the end of the signal. As before mentioned, the switch 345 and cam 345' is not used when this transmitter is used as a night watch transmitter.

The first digit of the code of this transmitter consists of a single tooth followed by an extra space in addition to the ordinary digit space. As with the type wheel designations as chosen, the second wheel will ordinarily not be used for night watch signals, there will then be a third space (see Fig. 10) causing no impulses to be directed to the second wheel and a blank space on the tape in that particular column. This will be apparent from the following description.

The operation for the first high current impulse is the same as above described, the first printer stepping magnet receiving one impulse bringing the designation "night watch station" into printing position. When the space is encountered during the transmission of the next line impulse, however, relay 411 is not energized, as contact 331 of relay 319 is open, and will not subsequently be energized during this signal as its circuit will be open at one or the other of the series contacts, 414, 413, 412 and 411', all of which are only closed simultaneously during the transmission of the second line impulse. However, routing relay 410 is operated at this time over the same circuit as previously explained for supervisory transmitters. When relay 304 subsequently releases, relay 423 is energized likewise as before. No impulse is, however, transmitted to the first stepping magnet as relay 403 is deenergized and contact 405 is open.

Due to the above mentioned additional space after the first tooth on the code wheel, the next line impulse is likewise of low intensity. However, relay 410 is deenergized at this time in the same way as explained for supervisory signals. When relay 304 subsequently deenergizes, relay 430 is energized likewise as before. As the following line impulse is again of low intensity, relays 319 and 403 will not operate but relay 432 will, through the same circuit as above traced for supervisory signals. Contact 405 of relay 403 being open, no impulse will, however, be directed to the second printer wheel when relay 304 subsequently releases. At that time relay 430 is deenergized as described above after the second code digit of supervisory signals. The following third and fourth impulse groups also operate in the same way. At the time the imprint magnet is energized, however, the circuit to the totalizer is not closed as make contact 463 of relay 411 is open. A shunt is also applied to the lower winding of relay 343 from minus through contact 342' of relay 315', conductor 464, contact 461 of relay 417 to conductor 466, when plus is applied over contact 458 of relay 430 to the lower end of the coil of the night watch delinquency indicator reset magnet, as previously described; relay 343 fails to operate. The resistance of its winding being eliminated from the circuit of the reset magnet 465, current of sufficient intensity will flow to operate it and reset the night watch delinquency indicator back to zero. The Hopkins Patents No. 1,942,814 and No. 1,942,815 show delinquency indicators. As the delinquency indicator itself does not form part of this invention, it need only be mentioned that the minute impulse magnet 468 operates a pawl mechanism which advances the main movable element of the delinquency alarm toward an alarm position which will be reached if the night watch transmitter does not operate

and energize reset magnet 465 (as explained above) in time to prevent. If the alarm position is reached, said movable element will operate a special transmitter constructed and connected as in Fig. 1. To this end, said movable element will push the leftwardly biased transfer element of the starting switch to contact 109, and record a delinquency alarm on the tape and on the totalizer, as above explained of the supervisory transmitter.

Should the night watch signal subsequently come in, the delinquency reset magnet 465 will be energized, allowing said movable element and said transfer element to restore to normal.

Fire alarm transmitter

The fire alarm transmitter Fig. 7 is very similar to the night watch transmitter. Being one of the alarm transmitters, it is connected to the alarm circuit. It is actuated by a latch contact. To trip the latch contact 12, the operator pulls on the lever 72a provided on the front of the station housing 72b. This breaks the glass rod 72c, and then withdraws the plunger 72d against the cam 72e of the latch 12, thus releasing the latch 12. The spring 72f restores the lever, and the switch 71 is restored to the normal position by the master cam after transmission, even though the glass rod has not been replaced. Subsequent operation can be obtained by pulling on the lever, even though the glass rod has not yet been restored. This transmitter is equipped with gears to provide for a multiple round signal, i. e., the master cam and restoring and master cams and contacts are operated by a geared shaft which is geared to the main or motor shaft in such a way that said contacts will be maintained in the operated position for 6 consecutive signals or 3 revolutions of the main or code wheel shaft, both sides of the code wheel having exactly the same code.

When the transmitter is started, due to the closing of the latch contact, it will operate the system in a similar way as explained above for the supervisory transmitters except that the operation will involve starting relays 203 and 216 and relays 202 and 207 (Fig. 2) instead of 103, 116, 102 and 107 (Fig. 1).

Start of pulsing relays for alarm signals

The pulsing relays are started by applying plus through contact 228 of relay 216, conductor 221, contact 306 of relay 315 to conductor 307. Again relay 304 is energized, then relay 305, then relay 304 is deenergized closing a circuit from plus through contacts 312, 313, conductor 314' contact 223, conductor 224, and through coil of relay 315' and contact 316 to minus, operating master alarm relay 315' which locks in to plus through contact 317, conductor 307, contact 306, conductor 221 and contact 220. Impulses are now transmitted to the running line R, of the alarm circuit through contact 320' of relay 315', the conditions exactly corresponding to those of the supervisory circuit as explained above.

The first digit of the fire alarm code consists of two teeth followed by a single space (Fig. 13). It will be remembered that the fact whether or not there is a tooth after the first tooth of the first digit is decisive for operating the relay 417 or not. As there is a tooth in this case after the first one, the 417 relay will be operated, this time through contact 367' of relay 315, and conductor 369, instead of contact 367 as previously. Otherwise the operation is the same as explained above

for supervisory transmitters with contact 335' taking the place of 335.

Automatic speed change for gong operation

When relay 430 is operated through resistor 429 and its right-hand winding at the termination of the low current impulse following the first digit, relay 350 is operated in multiple therewith through contact 483 of relay 417 over conductor 351, its upper winding over conductor 356 and through contact 507 (Fig. 5) to minus. This contact is operated by a cam coupled to the first type wheel. Normally and in the first and second position, sometimes also in the third position, contact 507 is closed and open in the other positions. Relay 350 locks in from plus through contact 352, its lower winding, conductor 411 and through the printer latch contact L to plus until the printer has been restored after recording the signals. By closing contacts 353 and 354, relay 350 connects another winding of relays 304 and 305 in multiple with their normal operating windings. The pulsing speed of the relays is thereby reduced to a degree as consistent for gong operation. This for the following reason: The timing of the impulses depends mainly on the release time of the relays. As the release is caused by reciprocal shunting of the windings, it is slow on account of the induction effect whereas the pick-up is fast, representing a small percentage of the pulsing time. Now the decay of the flux in a shunted magnet follows the law

$$\phi = \phi_0 e^{-Rt/L}$$

(where ϕ_0 is the flux before shunting, t the time in seconds, R the resistance and L the inductance of the winding) or

$$t = \frac{L}{R} \ln \frac{\phi_0}{\phi} = \frac{cn^2}{R} \ln \frac{\phi_0}{\phi}$$

(where n is the number of turns and c is a constant for a given relay). This formula shows that the release time of a shunted relay can be changed greatly by changing the resistance or number of turns of its winding or both.

With relay 350 operated, the impulses to the second, third and fourth stepping magnets of the printer will also operate gongs. The circuit for these stepping magnets was traced above through contact 436 of relay 432. From there a branch circuit extends over conductor 469, contact 355 of relay 350 and through the gong or gong contact 357 to minus.

Otherwise the operation is as explained above for supervisory transmitters except that relay 432 is operated during the first high current line impulse of the second digit through contact 349 of relay 319 instead of 331 of relay 315.

At the time the imprint magnet is operated, the circuit to the totalizer is not closed, as contact 342' of relay 315' is open. This contact also keeps the shunt across the lower winding of relay 343 open, so it will operate and give a special attention signal.

Alarm transmitter maintained in operation after printing

It will be recalled that relay 315 is deenergized at the time of the printing operation. This is not the case with 315' as its locking circuit through contact 317' is connected directly to conductor 307 which is now connected to plus at contact 220 of relay 216 as explained. However, the operation of the pulsing relays is stopped in the same way at this time as only relay 423 is energized and the contacts 401, 449, 447 and 75

435 are all open. The pulsing relays will, therefore, immediately start to transmit impulses over the line circuit when contact 401 of relay 432 closes following the printer resetting operation at which time the latch contact L opens and causes relay 432 to release. The locking circuit of relay 350 through conductor 411 and contact L, as explained above, is likewise deenergized. The higher speed of pulsing will then be resumed. 10 At the same time, a circuit is closed from plus through contact 367' of relay 315', conductor 368, contacts 411', 412, 413, 470 and 471 and through the left-hand winding of relay 472 to minus, operating relay 472 which locks in from minus through its contact 473 and right hand winding to conductor 369.

When the first high current impulse of the second round is transmitted, the operation starts again with relays 319 and 403 energizing as previously, etc. However, during the transmission of the second high current impulse, with relay 472 energized, a circuit is closed from plus at conductor 369, through contacts 411' of relay 430, 412, 413, 414, conductor 415, contact 331, conductor 332, contact 478, the middle winding of relay 417 to minus. This winding sets up an equal and opposing flux with respect to the right-hand holding winding neutralizing the flux of the relay 417 and causing it to release.

30 The operating circuit for relay 350 during this round extends through contact 484 of relay 472 instead of 483 of relay 417. The rest of the operation is the same as for the first round.

When the printer has been reset after the 35 second round, a similar circuit is closed for relay 472 which can be traced from conductor 369 through contacts 411-413, 470, 480, and the middle winding of relay 472 to minus. Middle and right-hand winding neutralize one another 40 causing relay 472 to release.

45 Relay 315' again remains energized. The third round operates exactly the same way as the first, operating relay 417 during the second code impulse and relay 412 after resetting the printer. The fourth round operates the same way as the second, deenergizing relay 417 during the second code impulse and relay 472 at the end of the signal. The fifth and sixth round, operate exactly as the first and second respectively so that relays 417 and 472 will be restored to the normal deenergized position at the end of the alarm signals transmitted by the transmitter.

55 After the printer has been operated for the last recording, the transmitter is kept operating until it reaches its home position where the master cam contacts of the transmitter are restored to the position shown on the drawings. Unless another transmitter is already connected to the running line, the following line impulse will find the line open causing relays 203 and 216 to release 60 in the same way as described above for relays 103 and 116 for the supervisory circuit. Contact 223 opens, and when relay 385 releases the next time, opening contact 312, the circuit of the pulsing relays will be open as well as that of relay 315' which releases.

Waterflow signals

70 The waterflow transmitter (Fig. 2) has a main motor and code wheel shaft and a geared shaft somewhat as in Fig. 6 and is adapted for restoration signals somewhat as in Fig. 1. It is also provided with means for giving an extra impulse for tamper signals.

The shafts are geared to give one rotation of

the geared shaft to each two rotations of the main or motor shaft. As will be later explained, the code wheel gives waterflow signals during one and one-half rotations of the code wheel and a restoration signal during one-half rotation of the code wheel. This allows the transfer cam, which is preferably on the motor shaft, to operate to effect transfer within a movement of 180 and 360 degrees from normal and requires that the master cam 14' operate the master switch at 270 and 360 degrees from normal. Hence the master cam is not symmetrical.

The waterflow switch (Fig. 2) may be operated by a flow detector, as is well known, and when operated a circuit is closed from plus available on the starting line ST through alarm contact 210 of the transfer cam 14' contact assembly, through the normally open contact 209 of the W. F. switch and through thermostat heater winding 250 to negative available on the C line. The thermostat 251 starts to heat up. In case the W. F. switch is operated on account of water hammer in the piping system, it does not stay closed long enough to permit the thermostat to operate, which will then again cool off when the flow detector restores its switch to normal, and nothing further happens. This arrangement thus prevents false alarms that would otherwise be caused by surges in the water pipes.

In case of actual operation, the thermostat finally closes its contact 251 thereby energizing the transmitter from plus at the starting line through contacts 210, 251, 211 and the right hand magnet coil to negative available at the C line. Further operation for water flow is the same as described above of Fig. 1.

In operating the thermostat also moves a latch under the tip of pen spring 253 preventing it from later closing the associated contacts when the tooth of cam 254 has been rotated out of the way. This feature will be more specifically referred to when discussing tamper signals. At the end of the water flow signals, the master cam restores the master switch to normal.

Waterflow signals are arranged for repeated operation; in the disclosed form of the system three signals are transmitted. Like supervisory transmitters, the waterflow transmitters have to transmit a waterflow alarm signal and in addition a restoration signal when the waterflow switch restores to normal. The code wheel is cut for the alarm code on one side and the restoration code on the other side. This restoration code is, however, identical with the code on the alarm side except that the second tooth of the first digit is cut off. The first digit on the alarm side consists of three teeth followed by two spaces (Fig. 11). Arrangement is made for distinctive tamper signals. If the transmitter is operated on account of tamper, an additional high current impulse, later to be explained, is transmitted, by means of a cam and associated contacts, instead of the first spacing or low current impulse after the first digit of waterflow signals.

Waterflow alarm signals.—The first round of alarm signals is transmitted by the alarm side of the code wheel. As just mentioned, the first digit of the alarm code consists of three teeth followed by two spaces. The second tooth, as previously explained will operate relay 417, in the same way as above explained. The first stepping magnet operates three steps bringing the type of the words "waterflow alarm" into printing position. When relay 304 releases following the transmission of the first low current or space impulse

after the first digit, relay 430 is energized as usual, also relay 358 as for fire alarm signals, if contact 507 is arranged to be closed in position 3 of the 1st type wheel, i. e., if waterflow signals are to operate the gongs. The following impulse is again a low current impulse but relay 432 is not energized at this time as both contacts 337 of relay 315 and 349 of marginal relay 319 are open. It is, however, operated through contact 348 of relay 319 during the first high current impulse of the second digit, starting the operation of the second stepping magnet. The second, third and fourth digits operate in the same way as for fire alarm signals. If relay 358 is energized, these digits will also operate gong 351. Relay 412 is likewise operated at the end of the printer operation.

The waterflow transmitter is provided with gears which are arranged for a three-round alarm signal, i. e., one and one-half revolutions of the code wheel shaft. After the first alarm round has been recorded, the transmitter remains in operation and the second round is transmitted by the other side of the code wheel which is identical to the first except the second tooth of the first digit is missing as in Fig. 12. This means that the second line impulse will be of low current intensity and the circuit which causes relay 417 to release on the second round of a fire alarm signal is ineffective due to contact 331 of relay 319 being open. However, when relay 304 subsequently releases, an impulse is transmitted to the first stepping magnet although contact 405 is open. This circuit can be traced from plus through contacts 327 of relay 304, 358 of relay 315', conductor 359, contacts 481, 482, conductor 407 and through the coil of the first stepping magnet PS1 to minus so that the first stepping magnet will obtain three impulses as on the previous round. At the end of this signal, which otherwise operates the same as the first round, relay 412 is already energized and no change takes place as far as it is concerned. The transmitter continues to operate for its third round which again is transmitted by the same side of the code wheel as the first as in Fig. 11. The second code impulse is of high current intensity and causes relay 417 to release as explained above for the second round of fire alarm signals. Relay 358 is operated during this round through contact 484 of relay 412 instead of contact 483. At the end of the third round, relay 412 is deenergized in the same way as for the second round of fire alarm signals. After completing its cycle, the transmitter will restore its master cam contacts to the normal condition and cause the control center relays to restore as previously explained.

It will be noticed that at the end of the third round of alarm, both relays 417 and 412 are de-energized and ready for a new counting cycle.

Waterflow restoration signal

When the waterflow stops, the waterflow switch returns to the normal position as illustrated. A starting circuit can then be traced from line ST through restoration contact 252, which is now closed (as the transfer cam has been shifted 540 degrees, 3 rounds of signals having been transmitted) through the normally closed contacts 209 of the W. F. switch and the tamper switch through contact 211 of the master switch and the right hand magnet to the C line. The code will now be transmitted by the restoration side of the code wheel as in Fig. 12. As will be recalled, the restoration code has a

space following the first tooth. This means that relay 417 will not be operated during the transmission of that particular impulse. However, as explained above, in connection with the second round of waterflow alarm signals, the first stepping magnet will nevertheless obtain three impulses.

In addition, a circuit for the second stepping magnet is simultaneously closed. This can be traced from plus through contacts 321, 358, conductor 359, contacts 481, 485, 487, 488 over conductor 438 and the coil of the second stepping magnet PS2 to minus. When the first printing magnet receives its third impulse, the second stepping magnet receives its second additional impulse, but through contact 486 instead of 485. It will furthermore receive two additional impulses when magnet 304 releases following the two low current space impulses after the first code digit. It will then be operated in the regular way controlled by the second code digit. It will be seen that the second stepping magnet thus receives a total of four additional special impulses which with the addition of the three regular impulses later received, serve to advance the type wheel to the restoration position. The rest of the operation is the same as explained before. As both contacts 483 and 484 are open, relay 358 is not operated, the pulsing speed is not changed nor are the gongs operated. When the printer is reset, the transmitter continues to operate until it completes one-half revolution. The master cam of the transmitter is cut in such a way that its contacts will resume their normal condition after the transmission of the restoration signal so that only one recording is obtained.

Waterflow tamper signals

If someone opens the transmitter housing 210', the tamper switch is moved to its lower position by any suitable means, for instance a spring 211' when the housing releases the vertical rod 212' pivoted to an extension of the switch transfer element. This causes a distinctive tamper signal. In that case the starting circuit can be traced from the ST line through contact 210, the normally open contact 214' of the tamper switch, contact 211, the right hand motor winding to line C.

As the transmitter starts with the thermostat in its normal condition, the latch operated by the thermostat in case of waterflow is not in position to engage pen spring 253. After cam 254 has been rotated slightly, pen spring 253 drops off the tooth and closes the associated contacts. It will be noticed that the contacts of cam 255 are thereby connected in multiple with the coding contacts. The tooth of cam 255 is so arranged that the associated contacts are closed for one step at the time the main coding contacts are opened at the end of the first digit of the code. An additional high current impulse is thus transmitted. This causes the first type wheel of the printer to be advanced to the fourth position bringing "WF tamper" into printing position. The rest of the operation is the same as for waterflow alarm signals. Relay 358 and the gongs are not operated as contacts 507 is open in position 4 of the 1st type wheel.

Waterflow tamper restoration

When the tamper contacts are restored to the normally closed position, the transmitter is started as for waterflow restoration signals. However, the additional impulse will also be

added at the end of the first digit again causing the designation "WF tamper" to be recorded on the printer, otherwise the recording is as explained above for waterflow restoration signal.

5 ALARM SIGNAL PRECEDENCE AND NON-INTERFERENCE AND SUCCESSION BETWEEN ALARM AND SUPERVISORY CIRCUIT

If an alarm transmitter is actuated at or about 10 the same time as a transmitter connected to the supervisory circuit, it will take precedence over it. In this case both relays 116 and 216, which may here be called precedence relays, will be energized. The operation of the pulsing relays will be 15 started with relay 304 pulling up, then relay 305 and then relay 304 releasing. A circuit is now closed from plus through contacts 312, 313, conductor 314', contact 223, conductor 224 and through the coil of alarm master relay 315' and 20 back contact 316 to minus. Supervisory master relay 315 cannot operate as contact 222, which supplies plus to contact 123 over conductor 314, is open.

If a transmitter on the supervisory circuit is 25 actuated first, it has to complete its signal in order to prevent interference but will let the alarm signal get in immediately after operating the printer. Assuming that while a transmitter is operating on the supervisory circuit, an alarm 30 transmitter is actuated, relays 203 and 216 will be operated but relay 315' cannot be energized immediately as back contact 316' of relay 315 is open. When, however, relay 315 releases at the 35 time of the printing operation, this contact closes again and relay 315' will operate as soon as the pulsing relays have started up and contact 312 closes. In this case the transmitter operated first on the supervisory circuit will not complete 40 its cycle until after all alarm signals have been cleared. It will then complete its remaining steps bringing the master cam back to the home position. This latter operation has been explained above in connection with the description of the supervisory transmitter.

45 Non-interference and succession of transmitters on the same circuit

In case several transmitters are actuated on 50 the same circuit at or about the same time they will be energized for the initial starting impulse for which current is derived from the ST line. When 315 or 315' operate, the starting line will be simultaneously deenergized by the opening of back contact 301 or 301' respectively; and the 55 transmitters operate their master cam contacts to the running position. It will be seen that the transmitter located nearest to the "out" side of the R line will be the only one to receive line impulses over the running line. After transmitting its signal and returning to the home position, this transmitter restores the running line to its normal condition and impulses will now be 60 directed to the second transmitter which again prevents impulses from reaching transmitters 65 waiting further back on the line.

In case of this happening on the alarm circuit, the transmitters waiting will come in successively one after another without relay 315' releasing between. It has, however, been pointed out that 70 the converting relays 411 and 472 are arranged to always complete a full cycle for each type of transmitter signal so as to be ready for a new counting cycle when a new transmitter starts to transmit.

Automatic trouble adjusting means and operation under trouble conditions

In case of a break on the ST or C line, the corresponding relay 102 or 202 is deenergized and closes a circuit for the trouble lamp. Assuming that the break occurs on the supervisory circuit, for instance, the release of relay 102 or 107 or both, causes the deenergization of the normally energized upper winding of adjusting relay 125. Relay 125 releases and cannot be re-operated through this winding as contact 126 opens. This relay closes a circuit to the alarm buzzer 348 (right of Fig. 3) over conductor 360 by closing its back contact 136 (lower part of Fig. 1). The buzzer can be silenced by the operation of the corresponding silencing switch 136.

In this connection it may be pointed out that in case of operation with the circuit at normal, relays 102 and 107 are also deenergized when the circuit of the starting and running line is interrupted by relay 116 and 315. However, relay 125 is held energized, as a multiple circuit is closed by contacts 128 of relay 103 and 129 of relay 116, also by contact 361 of relay 315 over conductor 130, keeping relay 125 energized during the transmission of the signal. After the release of relays 103, 116 and 315, relays 102 and 107 pick up again, closing the normal circuit for relay 125. As there is a slight interval of time between the restoration of the line circuits and the closing of the make contacts of relays 102 and 107, relay 125 is equipped with a copper slug in order to keep it energized during this interval. The arrangement for the alarm circuit is identical.

Relay 125 releasing in case of a break of a line conductor connects the two ends of the ST lines together and the two ends of the C lines together, respectively by contacts 131 and 132 so that plus and minus polarity respectively is fed to both ends of the respective circuits at the same time. Assuming now that a break in all three wires is the cause of the trouble, which is the most severe condition, all transmitters connected to the circuit will still be able to obtain plus and minus polarity over the ST and C lines respectively for the initial starting step when actuated. A transmitter located between the break in the R line and its "out" side will operate in the usual way starting the operation of the system by operating relays 103 and 116. If, however, the transmitter is located between the break and the "in" side of the R line, the closing of the armature contact will not operate starting relay 103 but operate relay 116 directly through the "in" side of the R line, contact 133, the right-hand winding of 116, contact 134 and the left-hand winding of 116 to plus. Relay 116 operates and closes the holding circuit for its left-hand winding through contact 118, resistor 119, over holding conductor 115 and through contact 303 to minus. As contacts 134 and 118 are of the make-before-break type, the circuit of relay 116 is never interrupted. Relay 116 starts the operation of the pulsing relays in the usual way. It will be seen, however, that impulses are now transmitted through back contact 135, the right-hand winding of relay 116 and back contact 133 over the "in" side of the R line, through the master cam contact 126 of the transmitter, its left-hand magnet coil and through the C line to minus. This magnet is capable of operating the transmitter in the same way as the right-hand one. Otherwise however, the operation is the same as under normal

conditions. The right-hand winding of relay 116 is similarly arranged as the left-hand winding of 103 to hold relay 116 energized during the transmission of impulses. The left-hand winding of 116, similarly as the right-hand winding of 103 is deprived of current during the time of impulse transmission due to contacts 303, 323 and 324 being open. This arrangement again serves the purpose of clearing the control center equipment when the transmitter gets off the line.

Non-interference and succession on a circuit with line troubles

The non-interference and successive operation is not affected by breaks in the ST and C lines.

In case of a break in the R line, transmitters operated simultaneously between the break and the "out" side of the R line will operate in the standard way. In case of transmitters operated simultaneously between the break and the "in" side of the R line, the one nearest to the "in" side will transmit its signal first operating the 116 or 216 relay directly as explained above. Otherwise the operation is the same as for normal conditions.

Simultaneous operation of transmitters on opposite sides of a break in the R line

If two or more transmitters are simultaneously actuated, for starting, on opposite sides of a break on the R line, the transmitters located between the break and the "out" side of the R line will operate the 103 relay and 116 relay in succession. Transmitters located between the break and the "in" side of the R line will directly operate the 116 relay as explained before. As the 116 relay breaks the operating circuit of the 103 relay by its contacts 104, the 103 relay may not have a chance to pick up if the transmitters are operated at exactly the same time. In that case, impulses will first be transmitted over the "in" side of the R line through back contact 135. After all the transmitters connected to that side of the circuit have transmitted their signal and the relay 116 is deenergized, relay 103 will be energized in series with the right-hand coil of the transmitter nearest to the "out" side of the circuit. Relay 103 operates relay 116 which starts the operation. The transmitters located between the break and the "out" side of the circuit will then transmit their signals in succession. The same applies, of course, to relays 203 and 216 of the alarm circuit.

RESTORATION OF CIRCUIT TO NORMAL AFTER REMOVING TROUBLE CONDITION

When the line breaks have been repaired, relays 102 and 107 or 202 and 207 respectively will, nevertheless, not pick up since relay 125 or 225 first has to restore the line circuit to its normal condition. These relays are provided with another winding (the lower ones). These windings are connected to the minute impulse contact over conductor 361 and are energized once every minute. The next minute impulse following the repair of the line circuit will cause the corresponding relay 125 or 225 to pick up. It will then lock in through its contact 126 or 226 respectively, as soon as the relays 102 and 107 or 202 and 207 pick up. At the end of the minute impulse, relay 125 or 225 will then stay energized leaving the circuit at normal.

When relay 125 or 225 operates, a circuit is closed for the buzzer through make contact 127 or 227 and the normally open side of the asso-

ciated silencing switch which previously has been operated. By throwing the switch back to normal, the buzzer can be silenced. Relays 102 and 107 or 202 and 207 when operated, extinguish the lamp which was lighted when they released.

As a time impulse may come in during the transmission of a signal on an abnormal circuit, it must be prevented from causing interference by energizing the corresponding 125 or 225 relay. This is obtained by connecting the restoring winding of these relays in series with a normally closed contact 137 or 237 respectively of the relays 116 or 216 respectively which contact will then be open.

From the above it will be clear that, if a transmitter starts after the line has been repaired but before the minute impulse has restored relays 125 or 225 respectively, the signal will nevertheless be received without fail.

Ground supervision and operation with grounded lines

The system is operated from an ungrounded battery. However, the center of the battery is connected through contacts 363, 363' and the coil of relay 362 to ground. If a ground occurs on any of the line wires, this relay will be operated and closing its contact 364 light a lamp. By closing its make contact 365, the buzzer 343 is operated. It can be silenced by operation of the associated silencing switch. Operation of the system with a single ground on the line wires does not interfere with the normal operation as the only other ground is through the very high resistance of relay 362. In addition this ground is removed as soon as relay 315 or 315' operate which then only leaves the accidental ground as the only one on the system. It will then have no effect at all.

If a ground occurs on two line wires simultaneously, it amounts to a short circuit between line wires and in most cases the line fuses will be blown except a ground on both the C line of the alarm and that of the supervisory circuit which will not interfere with the operation.

Automatic clearing after disarrangement of equipment

If in working on the relays, etc., the serviceman should accidentally operate any of the relays, they will not lock in, as all locking circuits are arranged to function during operation only. Such accidental operation will, therefore, not affect a succeeding signal. Only the special alarm relay 343 can lock itself, but this is made noticeable immediately by the audible and visual signals and furthermore has no effect on succeeding signals. It can, of course, be restored in the usual way by operation of the acknowledgement key.

If the printer stepping magnets are manually operated, while the equipment is idle, relay 432 will be immediately energized from minus through the printer latch contact L, which will then be closed, over conductor 411, through contact 363 and 368' over conductor 378 and through the right-hand winding of relay 432 to plus. This causes the operation of the printer release magnet RL through the same circuit as traced before. The release magnet restores all of the printer wheels to normal and opens the latch contact. The latter causes relay 432 to release again. It is therefore impossible to leave any part of the equipment in a condition that it will

interfere with the proper reception of a subsequent signal.

I claim as my invention:

1. A receiver having three or more impulse operated control magnets adapted to be operated in accordance with code signals; a totalizer switch comprising a transfer contact and contacts normally engaged and disengaged therewith; a cam responsive to a certain control magnet for closing the transfer contact on the normally engaged contact if the certain control magnet responds to certain codes and on the normally disengaged contact if said certain control magnet responds to other codes; a totalizer having an adding magnet and a subtracting magnet connected to said normally engaged and disengaged contacts respectively; a source of current; and means for supplying one polarity to said magnets and the other to the transfer contact.
2. In combination, a receiver having control magnets adapted to be energized by code signals; a plurality of transmitters, each having code means to transmit an alarm signal and a restoration signal, each signal comprising spaced groups of impulses, the alarm code signal comprising a characteristic number of impulses in a certain digit, the restoration code signal comprising a different number of impulses in said certain digit; means cooperating with the impulses and spaces for energizing the magnets in accordance with the signals; a totalizer switch comprising a transfer contact and contacts normally engaged and disengaged therewith; a cam responsive to the control magnet corresponding to said certain digit for closing the transfer contact on the normally engaged contact if the control magnet is energized by said characteristic number of impulses and on the normally disengaged contact if said corresponding magnet is operated by said different number of impulses; a totalizer having an adding magnet and a subtracting magnet connected to said normally engaged and disengaged contacts respectively; and means for supplying current of one polarity to said magnets and of another polarity to the transfer contact.
3. In combination, first and second sets of transmitters; first and second master means associated with said sets respectively each adapted to be energized by the starting of a transmitter of its associated set and to supply operating current to the transmitters during signaling; each transmitter of the first set and some transmitters of the second set having code means to transmit alarm signals comprising a second impulse in the first digit; other transmitters of the second set having code means to transmit signals comprising one impulse in the first digit followed by at least one space impulse; a totalizer for counting codes comprising a second impulse in the first digit; a delinquency reset means; means responsive to codes of transmitters of the second set comprising a space after the first impulse of the first digit for operating the reset means and preventing operation of the totalizer.
4. In a signaling system, a transmission line including a transmitter and a source of potential connected thereto, means in said transmitter for creating a control condition in said line, switching means connected to said line in response to said control condition, a source of pulsating current connected to said line by the switching means for driving said transmitter whereby it creates a control condition in said line and trans-

mits groups of code impulses, each group being separated by the control condition, marginal coding means connected to said line by said switching means and responsive to code impulses only, a receiver including a plurality of control magnets, each magnet being individual to a particular group of code impulses and switching means for connecting said control magnets to the pulsating source in accordance with the transmitted code comprising a code relay energized by said marginal code relay to complete a circuit to the first control magnet for the first group of code impulses and prepare a circuit for subsequent groups of code impulses to other control magnets, a first routing relay energized by the pulsating source when the second impulse of the first group of code impulses is received, a second routing relay energized by the first routing relay, a third routing relay energized during the space between the first and second code groups through a circuit prepared by the first two routing relays, a fourth routing relay energized during the first impulse of the second group of code impulses by said third routing relay, a circuit to the second control magnet closed by said routing relays whereby the second code group is printed, contacts operated by the code relay in response to a second space between groups and by the first routing relay in response to the pulsating source for deenergizing the second and third routing relays whereby a circuit is completed to the third control magnet for controlling the receiver in accordance with the code group for the third digit, contacts operated by the coding relay during the third space between groups for energizing the third routing relay and contacts operated by this relay for deenergizing the first routing relay whereby contacts controlled by the routing relays complete a circuit to energize the fourth control magnet in accordance with the group of impulses representing the fourth digit.

5. In a signaling system, a transmission line including a transmitter and a source of potential connected thereto, means in said transmitter for creating a control condition in said line, switching means connected to said line in response to said control condition, a source of pulsating current connected to said line by the switching means for driving said transmitter whereby it creates a control condition in said line and transmits groups of code impulses, each group being separated by the control condition, marginal coding means connected to said line by the switching means for and responsive to code impulses only, a receiver including a plurality of control magnets, each magnet being individual to a particular group of code impulses and switching means for connecting said control magnets to the pulsating source in accordance with the transmitted code comprising a code relay energized by said marginal code relay to complete a circuit to the first control magnet for the first group of code impulses and prepare a circuit for subsequent groups of code impulses to other control magnets, a circuit from said pulsating source to the control magnets and a plurality of routing magnets responsive to code impulses for connecting said control magnets to said circuits in accordance with the digits of said code.

6. In a signaling system, a transmission line including a transmitter and a source of potential connected thereto, means in said transmitter for creating a control condition in said line, switching means connected to said line in response to said control condition, a source of pulsating cur-

rent connected to said line by the switching means for driving said transmitter whereby it creates a control condition in said line and transmits groups of code impulses, each group being separated by the control condition, marginal coding means connected to said line by said switching means and responsive to code impulses only, a receiver including a plurality of control magnets, each magnet being individual to a particular group of code impulses and switching means for connecting said control magnets to the pulsating source in accordance with the transmitted code comprising a code relay energized by said marginal code relay to complete a circuit to the first control magnet for the first group of code impulses and prepare a circuit for subsequent groups of code impulses to other control magnets and routing means responsive to the code impulses for connecting the control magnets in accordance with the transmitted digits.

7. In a signaling system, a transmission line including a transmitter and a source of potential connected thereto, means in said transmitter for creating a control condition in said line, switching means connected to said line in response to said control condition, a source of pulsating current connected to said line by the switching means for driving said transmitter whereby it creates a control condition in said line and transmits groups of code impulses, each group being separated by the control condition, marginal coding means connected to said line by said switching means and responsive to code impulses only, a receiver including a plurality of control magnets, each magnet being individual to a particular group of code impulses and switching means for connecting said control magnets to the pulsating source in accordance with the transmitted code comprising a code relay energized by said marginal code relay to complete a circuit to the first control magnet for the first group of code impulses and prepare a circuit for subsequent groups of code impulses to other control magnets, first, second, third and fourth routing relays controlled by the code impulses and the pulsating source, contacts operated by all four relays for energizing and connecting the second control magnet to the pulsating source in accordance with the second digit of the code, contacts operated by the fourth routing relay in response to the space between the second and third digits for connecting the third control magnet to the pulsating source in accordance with the third digit of the code, and contacts controlled by the third and fourth routing relays in response to the space after the third digit for connecting the fourth control magnet to the pulsating source in accordance with the fourth digit of the code.

8. In a signaling system, a transmission line including a transmitter and a source of potential connected thereto, means in said transmitter for creating a control condition comprising a low current pulse and a signal condition comprising higher current pulses whereby several digits of a code separated by the control condition are transmitted, a pulsating source of current connected to said line in response to the control condition, a receiver including control magnets, a circuit from said pulsating source to the control magnets and a plurality of routing magnets responsive to code impulses for connecting said control magnets to said circuit in accordance with the digits of said code.

9. In a signaling system, a transmission line including a transmitter and a source of potential,

means in said transmitter for creating a control condition comprising a low current pulse and a signal condition comprising higher current pulses whereby several digits of a code separated by the control condition are transmitted, a receiver including control magnets and a routing means responsive to the code impulses and the control condition for energizing the control magnets in accordance with the transmitted digits.

10. In a signaling system, a transmission line including a transmitter and a source of potential connected thereto, means in said transmitter for creating a control condition and a signal condition whereby several digits of a code separated by the control condition is transmitted, a pulsating source of current connected to said line in response to the control condition, a receiver including control magnets, first, second, third and fourth routing relays controlled by the code impulses and the pulsating source, contacts operated by the fourth routing relay for connecting the first control magnet to the pulsating source in accordance with the first code digit, contacts operated by all four relays for energizing and connecting the second control magnet to the pulsating source in accordance with the second digit of the code, contacts operated by the fourth routing relay in response to the space between the second and third digits for connecting the third control magnet to the pulsating source in accordance with the third digit of the code, and contacts controlled by the third and fourth routing relays in response to the space after the third digit for connecting the fourth control magnet to the pulsating source in accordance with the fourth digit of the code.

11. In combination, means for supplying groups of high current code impulses separated by low current control impulses, marginal coding means responsive to said code impulses only, a receiver including a plurality of control magnets and routing means responsive to the marginal coding means and the control impulses for energizing the control magnets in accordance with the transmitted groups of code impulses.

12. In a signaling system, a transmission line including a transmitter and a source of potential, means in said transmitter for creating a low current control condition and a high current signal condition, both of the same length, whereby several digits of a code separated by the control condition are transmitted, marginal coding means responsive to code impulses only, a receiver including control magnets and a routing means responsive to said marginal coding means and the control condition for successively energizing the control magnets in accordance with the transmitted digits.

13. In combination, a receiver including a plurality of control magnets, each magnet being individual to a particular digit of a code signal and responsive thereto, first and second transmitters, the second transmitter having code means to transmit alarm and restoration signals, the alarm signals comprising a certain number of impulses in a certain digit, the restoration signal having a different number of impulses in the same digit, first and second master relays associated with said transmitters respectively, and adapted to be energized by the starting of the respective transmitters, a totalizer having an adding device and a subtracting device, means operative when the first master relay is deenergized for actuating one device when the control magnet corresponding to said certain digit is operated in response to alarm

signals and means operative when the same control magnet is operated in response to restoration signals for actuating the other device.

14. In combination, a receiver including control magnets, each magnet being responsive to a certain digit in a code signal and responsive thereto, a first and second transmitter, the second transmitter having code means to transmit alarm and restoration signals, the alarm signals comprising a certain number of impulses in a certain digit and the restoration signals comprising a different number of impulses in the same digit, first and second master relay means associated with the respective transmitters, each adapted to be energized by the starting of its respective transmitter, a totalizer switch having normally engaged and disengaged contacts and a transfer member, a cam responsive to a control magnet corresponding to said certain digit for closing the transfer contact and the normally engaged contact if such magnet is energized by an alarm signal and for closing the transfer contact with the normally disengaged contact if said magnet is energized by an alarm signal and for closing the transfer contact with the normally disengaged contact if said magnet is energized by a restoration signal, a totalizer having an adding magnet and a subtracting magnet connected to said normally engaged and disengaged contacts respectively, means cooperating with the first master relay means when deenergized for supplying potential of one polarity to said totalizer magnets and means supplying opposite polarity to the transfer member.

15. In combination, a receiver including a plurality of control magnets, each magnet being individual to a particular digit of a code signal, a transmitter having code means to transmit alarm and restoration signals, the alarm signal comprising a certain number of impulses in a certain digit and the restoration signal comprising a different number of impulses in the same digit, means for stepping the control magnets in accordance with the code signals, a totalizer having an adding device and a subtracting device and means for operating one device when the control magnet corresponding to said certain digit is energized by said certain number of impulses and for operating the other device when said control magnet is operated by said different number of impulses.

16. In a signaling system, a transmitter adapted to transmit code digits and a restoration signal, impulse generating means for driving the transmitter, a receiver operated thereby, code responsive means for switching impulses from the generating means to control the receiver in accordance with the code and stop the generating means at the end of the code, means for restoring the receiver to normal, means responsive to this restoration for starting the impulse generator whereby it drives the transmitter to a position where it is ready to send a restoration signal.

17. In combination, a receiver having three or more impulse operated control magnets adapted to be energized in accordance with a code, transmitters having code means to transmit code signals consisting of spaced groups of impulses, impulse means controlled by the transmitters for supplying impulses to energize the magnets in accordance with the signals, a printing magnet, means for stopping the impulse means and energizing the printing magnet after the last impulse of the signal, means influenced by operation of the printing magnet to restore

the receiver to normal, a cut-out switch in the printing magnet circuit, a casing for the receiver, and means operated by the casing when raised for opening the printing cut-out switch while maintaining the other elements of the system energized thereby preventing a printing operation and consequent restoration and loss of message when the casing is raised.

18. In a signaling system, a supervisory transmitter adapted to transmit a plurality of code digits including a prefix having a certain characteristic, an alarm transmitter adapted to transmit a plurality of code digits including a prefix having a different characteristic, an impulse circuit energized by operation of either transmitter, a master supervisory relay and a master alarm relay adapted to be energized by the impulse circuit in response to the supervisory transmitter or the alarm transmitter respectively for connecting the impulse circuit to the respective transmitters to drive them at normal speed, a receiver including a plurality of control magnets, a routing means controlled by the code signals for distributing the code digits to the proper control magnets, relay means for changing the impulse circuit to reduce the frequency of pulsing whereby a transmitter may be driven at less than normal speed, a gong connected to said routing means by the relay means whereby it repeats the code and a circuit closed by the routing means and the receiver in response to the alarm prefix, only, for energizing the relay means whereby alarm codes are repeated by the gong at a slow rate.

19. In a signaling system, a transmitter adapted to transmit a prefix digit comprising a given number of impulses followed by a control condition and a plurality of digits separated by control conditions, a second transmitter adapted to transmit a different prefix digit comprising a different number of impulses followed by a control condition and a plurality of digits, an impulse circuit energized by operation of either transmitter, a master supervisory relay and a master alarm relay adapted to be energized by the impulse circuit in response to the supervisory transmitter or the alarm transmitter respectively for connecting the impulse circuit to the respective transmitters to drive them at normal speed, a receiver including a plurality of control magnets, a routing means controlled by the code signals for distributing the code digits to the proper control magnets, relay means for changing the impulse circuit to reduce the frequency of pulsing whereby a transmitter may be driven at less than normal speed, a gong connected to said routing means by the relay means whereby it repeats the code and a circuit closed by the routing means and the receiver in response to said different prefix, only, for energizing the relay means whereby alarm codes are repeated by the gong at a slow rate.

20. In a signaling system, a transmitter adapted to transmit a prefix digit comprising a given number of impulses followed by a control condition and a plurality of digits separated by control conditions, a second transmitter adapted to transmit a different prefix digit comprising a different number of impulses followed by a control condition and a plurality of digits, an impulse circuit energized by operation of either transmitter for driving either transmitter at a normal rate, a receiver for receiving code signals transmitted by either transmitter, a gong adapted to be actuated in response to code signals from the

5 second transmitter only, a routing means responsive to code impulses for actuating the receiver and gong and means for changing the impulse circuit to reduce the frequency of pulsing and connect the gong to the routing means whereby the gong and receiver repeat the code when the second transmitter operates.

21. In a signaling system, at least two transmitters adapted to transmit code impulses, one transmitter transmitting a code comprising a different prefix from that transmitted by the other transmitter, a receiver adapted to receive the code signals transmitted by either transmitter, a gong adapted to repeat code impulses transmitted by 10 only one of said transmitters, means to operate a transmitter and the receiver at a normal speed in response to code impulses and means to operate the transmitter, the gong and the receiver at a different rate in response to the different prefix signal transmitted by one of said transmitters.

22. In a signaling system, a transmitter adapted to transmit a plurality of code digits, each digit being separated by one or more control conditions, an impulse circuit energized by the transmitter operation, a master alarm relay energized by the impulse circuit for connecting the impulse circuit to the transmitter for driving the same at normal speed, an alarm receiver including a plurality of control magnets, a routing means controlled by the code signals and the control condition between digits for controlling the control magnets in accordance with the digits of the code, relay means for changing the characteristics of said impulse circuit to reduce the impulse frequency whereby the transmitter is driven more slowly, a gong connected to said routing means by the relay means whereby it repeats the code and a circuit closed by the routing means and the receiver in response to the code digit having a certain characteristic for energizing the relay means whereby the code is repeated by the gong at a slow rate.

23. In a signaling system, a transmitter adapted to transmit a plurality of code digits, each digit being separated by one or more control conditions, an impulse circuit energized by the transmitter for driving the same, a receiver adapted to receive code signals, a gong adapted to repeat the code signals and means responsive to actuation of said receiver by the first code digit for reducing the impulse rate of said impulse circuit.

24. In a signaling system, a supervisory line including supervisory alarm transmitters, an alarm line including alarm transmitters, each type of transmitter in both of the lines being adapted to transmit code signals having identifying prefixes, an impulse circuit for driving said transmitters, routing means responsive to the prefixes for distributing the digits of the codes and a receiver having control magnets adapted to be energized by said routing means in accordance with the codes.

25. In a signaling system, a supervisory line including supervisory transmitters and night watch transmitters, an alarm line including waterflow alarm transmitters and fire alarm transmitters, each type of transmitter in both of the lines being adapted to transmit code signals having identifying prefixes, an impulse circuit for driving said transmitters, routing means responsive to the prefixes for distributing the digits of the codes, a receiver having control magnets adapted to be energized by said routing means in accordance with the codes, a gong adapted to repeat signals originating in the alarm line and means responsive

to the routing means and the receiver when an alarm prefix is received for changing the pulsing rate of the impulse circuit and connecting the gong to the routing means whereby alarm signals are repeated at a slower rate than supervisory signals.

26. In a signaling system, a waterflow transmitter adapted to transmit a code signal including a characteristic prefix and a restoration signal, a receiver having control magnets for registering the code impulses, an impulse circuit for driving said transmitter and said receiver, means for stopping said impulse circuit and transmitter at the end of the code, means for restarting said impulse circuit and transmitter for transmitting restoration signals and means responsive to the restoration signals for adding impulses whereby the second magnet of said receiver registers a restoration signal.

27. In a signaling system a waterflow transmitter adapted to transmit a code signal including a characteristic prefix and a restoration signal, a receiver for registering the code impulses, means for driving said transmitter and said receiver in accordance with code impulses, means for stopping said transmitter and impulse circuit at the end of the code and means responsive to the characteristic prefix for restarting said impulse circuit and transmitter and for adding impulses whereby the receiver registers the restoration signal.

28. A code receiver having control magnets adapted to be energized in accordance with code signals, a totalizer having an adding device and a subtracting device, and means for operating one device when a certain control magnet is operated in accordance with particular code signals and to operate the other device if said certain control magnet is operated in accordance with other code signals whereby the totalizer indicates the net number of the different codes which have been received.

29. In a signaling system, a transmitter for transmitting successive rounds of alarm code signals and restoration code signals, the alarm signals comprising one digit characteristic thereof, the restoration signal also comprising one digit characteristic thereof, a code translating means responsive to the code signals for distinguishing between an alarm signal and a restoration signal, a recorder controlled by the code translating means for making a record of the codes and means for counting a predetermined number of rounds and restoring the system to normal whereby a subsequent and first transmitted restoration signal may be recorded.

30. In a signaling system, a transmitter including a code wheel adapted to transmit in succession an alarm code comprising a certain arrangement of current impulses and a restoration code comprising a different arrangement of current impulses, switch means for starting the transmitter, an alarm relay responsive to the starting operation, an impulse generating circuit responsive to the alarm relay for driving the transmitter, means at the transmitter for converting said impulses into code current impulses in accordance with the code cut on the code wheel, a marginal code relay responsive to code current impulses, a receiver comprising a number of control magnets each of which responds to a certain digit of the code, an energizing circuit connected to each magnet, switching circuits controlled by the impulse generating circuit and the marginal code relay

for successively energizing the magnets in accordance with the digits of the code, an auxiliary circuit connected to one of the magnets for energizing the same and controlled by the impulse generator, the alarm relay and the marginal code relay and a converting relay controlled by the marginal code relay and the alarm relay for opening the auxiliary circuit when a certain code is transmitted.

10 31. In a signaling system, a transmitter for transmitting in succession an alarm code comprising a certain arrangement of current impulses and another code comprising a different arrangement of current impulses, an alarm relay responsive to transmitter operation, an impulse generating circuit responsive to the alarm relay, a code relay responsive to current impulses, a receiver comprising a number of control magnets, each magnet responding to a certain digit of the code, an energizing circuit connected to each magnet, switching circuits for successively energizing the circuits to each magnet in accordance with the digits of the code, an auxiliary energizing circuit connected to one of the magnets for energizing the same and controlled by the impulse generating circuit and the alarm relay and a converting relay controlled by the marginal code relay for opening the auxiliary circuit when said alarm code is transmitted.

20 32. In a central office switching circuit, a plurality of control magnets each of which responds to the code digit signals in succession, an impulse generator, a marginal code relay responsive to signals, an auxiliary code relay responsive to 35 operation of the marginal relay by the first impulse signal of the first digit for closing a circuit to the first control magnet, a latch contact closed by the first control magnet, a first routing relay energized by the second code impulse signal of the first digit through a circuit closed by the impulse generator and the latch contact, a converting relay energized by the marginal relay and the routing relay in response to this same code impulse signal, other routing relays responsive to 40 operation of the marginal code relay by subsequent code signals for establishing a circuit to the second control magnet for receiving the second digit of the code and a second circuit controlled by the converting magnet for energizing 45 the second control magnet by signals additional to the code transmitted.

33. In a central office switching circuit, a plurality of control magnets each of which responds to certain code digits, a source of code impulses, 50 a marginal code relay responsive to code impulses, first switching means responsive to operation of the marginal relay for closing a circuit to the first control magnet, second switching means energized in accordance with the second impulse of the first code digit, a converting relay energized by the second switching means in response to this same code impulse, a third switching means responsive to operation of the marginal code relay by subsequent code impulses for establishing a 55 circuit to the second control magnet and controlling it in accordance with the code and a second circuit controlled by the converting relay controlling the second control magnet in accordance 60 with the characteristics of the first digit of the code.

34. In a signaling system, a transmitter for transmitting in succession an alarm code comprising a certain arrangement of current impulses and a restoration code comprising a different arrangement of current impulses either of which

may be initially transmitted, a receiver controlled from the transmitter and comprising a number of control magnets each of which responds to a certain digit of the code, means for switching successive digits to their respective magnets, an auxiliary circuit controlled from the transmitter and connected to one of the magnets for adding impulses to convert a transmitted digit into another digit and a selecting device controlled in accordance with the characteristics of the first digit of the code for opening the auxiliary circuit when an alarm code is transmitted.

35. In a signaling system, a transmitter for transmitting in succession a code comprising a certain arrangement of current impulses and another code comprising a different arrangement of current impulses, a recording device controlled in accordance with the codes, and means controlled in accordance with the first digit transmitted for controlling the recording device to effect conversion of one of the codes to the other code.

36. In a signaling system, a transmitter for transmitting successive rounds of alarm signals and restoration signals, the alarm signals comprising several digits the first of which includes at least two current impulses, the restoration signal comprising several digits the first of which includes a current impulse followed by a spacing signal, a code relay actuated by current impulses, a recorder controlled by the code relay for making a record of the codes, a first converting relay controlled by the code relay for effecting recordation of the restoration code as an alarm code when the alarm code is the first to be transmitted, a second converting relay for counting the rounds of the code signals, a plurality of routing relays responsive to successive digits of the code for routing signals to the receiving means and setting up a circuit for the second converting relay whereby release of the routing relays at the end of the first round energizes the second converting relay, a locking circuit established by the second converting relay for holding itself in actuated condition through the second round of code signals, a neutralizing circuit established by the routing relays on the second impulse of the first digit of the third round of code signals for releasing the first converting relay and a circuit for neutralizing the second converting relay and releasing the same at the end of the third round of signals completed by the first converting relay when it releases whereby successive rounds of code signals are counted and the system is prepared for reception of a restoration code from a different transmitter.

37. In a signaling system, a transmitter for transmitting successive rounds of alarm signals and restoration signals, the alarm signals comprising several digits the first of which includes at least two current impulses, the restoration signal comprising several digits the first of which includes a current impulse followed by a spacing signal, a code relay actuated by marking signals, a receiver controlled by the code relay for making a record of the codes, a first converting relay controlled by the code relay for effecting recordation of the restoration code as an alarm code when the alarm code is the first to be transmitted, a second converting relay controlled and energized by the first converting relay for preparing a neutralizing circuit which is completed by the code relay in response to the second impulse of the first digit of the third round of signals whereby the first converting relay is released, and a neutralizing circuit completed by the release of the first converting relay at the

cessation of code signals for causing the release of the second converting relay whereby normal conditions are restored and the system is prepared for recording of subsequent codes.

5 38. In a signaling system, a transmitter for transmitting successive rounds of alarm signals and restoration signals, the alarm signals comprising one digit characteristic thereof, the restoration signal also comprising one digit characteristic thereof, a code translating means responsive to the code signals for distinguishing between an alarm signal and a restoration signal, a receiver controlled by the code translating means for making a record of the codes, means controlled by the translating means for effecting recordation of the restoration code as an alarm code when the alarm code is the first to be transmitted, and means for counting a predetermined number of rounds to effect restoration of the last named means to normal whereby subsequent codes may be recorded.

20 39. In a signaling system, a transmitter for transmitting in succession an alarm code comprising a certain arrangement of current impulses and a restoration code comprising a different arrangement of current impulses, a receiving means for recording the codes, a code relay for controlling the receiving means in accordance with the transmitted code and a selecting device controlled by the code relay in accordance with the code first transmitted in point of time for governing the receiving means to effect repeated recording of the first transmitted code.

25 40. In a signaling system, a transmitter for transmitting in succession an alarm code comprising several digits, the first of which includes at least two current impulses, and a restoration code comprising several digits, the first of which includes a current impulse followed by a spacing signal, a receiving means for recording the codes, a code relay for controlling the receiving means in accordance with the transmitted code and a selecting device actuated by the code relay when it initially receives a pair of current impulses for actuating the receiving means to effect repeated recording of the alarm code.

30 41. In a signaling system, a transmitter for transmitting in succession one particular code and then a different code, a receiving means for recording the codes, a code relay for controlling the receiving means in accordance with the transmitted code and a selecting device controlled by the code relay in accordance with the code first transmitted in point of time for governing the receiving means to effect repeated recording of the first transmitted code.

35 42. In a signaling system, a transmitter including a code wheel adapted to transmit in succession a supervisory code comprising a certain arrangement of current impulses and a night-watch code comprising a different arrangement of current impulses, switch means for starting the transmitter, an alarm relay responsive to the starting operation, an impulse generating circuit responsive to the alarm relay for driving the transmitter, means at the transmitter for converting said impulses into signals in accordance with the code cut on the code wheel, a marginal code relay responsive to signals, a receiver comprising control magnets, an energizing circuit connected to each magnet, switching circuits controlled by the impulse generating circuit and the marginal code relay for successively energizing the magnets in accordance with the digits of the code, a totalizer for indicating

operated supervisory transmitters, a delinquency device for indicating night-watch delinquency, a delinquency reset, and a switching relay for energizing the totalizer in response to a supervisory code and energizing the delinquency reset in response to a night-watch code.

43. In combination, a plurality of transmitters embodying code means to transmit code signals

comprising current impulses of a definite predetermined value and other code signals comprising current impulses of a different type than the first mentioned code signals; a delinquency reset means; and means influenced by one of said types of code signals for operating said reset means.

MANFRED W. MUEHTER.
